UNITED STATES PATENT OFFICE.

LOUIS STIRLING HARRELL, OF BATON ROUGE, LOUISIANA.

OILER.

Application filed March 5, 1923. Serial No. 623,077.

To all whom it may concern:

Be it known that I, LOUIS STIRLING HARRELL, a citizen of the United States, and resident of Baton Rouge, in the parish of East Baton Rouge and State of Louisiana, have invented certain new and useful Improvements in Oilers, of which the following is a specification.

This invention relates to liquid dispensers 10 and more particularly to a means for dispensing a lubricant in desired quantities.

Briefly stated an important object of this invention is to provide a lubricant dispenser having simple and reliable means whereby 15 the oil cups located at an elevated point on an engine or other piece of machinery may be conveniently lubricated at frequent intervals from a point below.

A further object is to provide a lubricator 20 of the character specified which is of highly simplified construction, simple to operate and cheap to manufacture.

Other objects and advantages will be apparent during the course of the following 25 description.

In the accompanying drawing forming a part of this application and in which like numerals are employed to designate like parts throughout the same,

30 Figure 1 is a side elevation of the improved lubricant dispenser in its inoperative position.

Figure 2 is a fragmentary side elevation of the improved lubricator in its operative 35 position.

Figure 3 is a fragmentary rear elevation of the improved lubricator.

In the drawing wherein for the purpose of illustration is shown a preferred embodiment of the invention the numeral 5 designates a standard which consists of a plurality of sections joined by coupling members or nipples 6. Of course, any desired number of sections may be employed 45 and consequently the standard or staff 5 may be made of variable length.

Figures 1 and 2 illustrate that the upper portion of the standard 5 is provided with a loop or yoke 10 having an attaching stem 50 11 secured to the standard by means of the fastening member 12. In carrying out the invention the lubricant container 14 is provided at its upper end with a pair of apertured ears 15 rotatably mounted upon a transversely extending rod or pivot pin 16,

the ends of which are securely connected to the upstanding sides of the yoke 10.

With reference to Figure 1 it will be seen that the lubricant container 14 which is rotatably connected to the pivot element 16 60 is provided with a discharge spout 20 by means of which the lubricant may be discharged into the funnel 22. The funnel 22 encloses the major portion of the lubricant container 14 and is provided with an 65 outwardly inclined discharge spout 25 by means of which oil discharged into the funnel may be supplied to oil cups at elevated points.

The oil container 14 may be swung about 70 the axis of the pivot element 16 by a cable 125 connected to the casing at 26 to the lower end of the lubricant container. The cable 125 is also trained about a pulley 28 carried by the depending terminal portion 75 29 of a laterally projecting arm 30 of the yoke 10. In carrying out the invention the lower portion of the cable 125 is trained about a pulley or reel 35 secured to any desired portion of the standard 5 by means 80 of a bracket 36.

In use a lubricant is supplied to the container 14 by means of a filler branch 40 and the discharge spout 25 may be positioned at the desired point for discharging the 85 lubricant into the oil cup or the like of the machinery. The reel 35 may now be rotated by means of a handle 42 and the oil container will be tilted for discharging the oil into the funnel 22 whereupon it will flow into 90 the spout 25 and the final lubricant receiver.

With reference to the foregoing description taken in connection with the accompanying drawings it will be seen that the oil cups at elevated points may be conveniently lubricated and that the device is not likely to get out of order.

Having thus described the invention, what is claimed is:—

1. A lubricant dispenser comprising a 100 standard, a yoke connected to the upper portion of the standard, and having spaced sides, a pivot pin connected to the spaced sides, a lubricant containing receptacle having apertured ears rotatably connected to 105 said pivot pin between the sides of said yoke, and a funnel rigidly connected to said yoke and having a depending spout adapted for discharging the oil into an oil receiver.

2. A lubricant dispenser comprising a 110

standard, a loop-shaped yoke rigidly connected to the upper portion of said standard and having a rearwardly projecting arm, a transversely extending pivot rod connected at its ends to the sides of said yoke, a lubricant container having its upper end provided with ears rotatably connected to said pivot rod, said lubricant container being provided with a discharge spout, a funnel rigidly connected to said yoke and having a depending discharge member, and a flexible element connected to the lower end of said lubricant container and having sliding connection with said arm.

15 3. A lubricant dispenser comprising a standard, a loop-shaped yoke rigidly connected to the upper portion of said standard and having a rearwardly projecting arm, a pivot rod connected at its ends to the sides of said yoke, a lubricant container having its upper end provided with ears rotatably connected to said pivot rod, said lubricant container being provided with a discharge spout, a funnel rigidly connected to said yoke and having

20 a depending discharge member, a flexible

element connected to the lower end of said lubricant container and having sliding connection with said arm, and a reel having connection with said standard, the lower portion of said cable being trained about 30 said reel whereby the oil container may be tilted by rotating said reel.

4. A lubricant dispenser comprising a standard, a yoke connected to said standard and having an arm, a pivot rod connected 35 at its ends to the sides of said yoke, a lubricant container having its upper end provided with ears rotatably connected to said pivot rod, said lubricant container being provided with a discharge spout, a funnel 40 connected to said yoke and having a discharge member, a flexible element connected to the lower end of said lubricant container and having sliding connection with said arm, a reel having connection with said standard, the lower portion of said cable being trained about 45 said reel whereby the oil container may be tilted by rotating said reel.

LOUIS STIRLING HARRELL.
